LEE DE FOREST, OF NEW YORK, N. Y., ASSIGNOR, BY MESNE ASSIGNMENTS, TO DE FOREST
RADIO-TELEPHONE CO., A CORPORATION OF NEW YORK.

WIRELESS-TELEGRAPH TRANSMITTER.

No. 926,935.

Specification of Letters Patent.

Patented July 6, 1909.

Application filed February 2, 1906. Serial No. 299,090.

To all whom it may concern:

Be it known that I, LEE DE FOREST, a citizen of the United States, and a resident of New York, in the county of New York and State of New York, have invented a new and useful Improvement in Wireless-Telegraph Transmitters, of which the following is a specification.

My invention relates to wireless telegraph transmitting systems and more especially to long distance transmitting systems in which large amounts of electrical energy are radiated in the form of electromagnetic waves.

One object of my invention is to provide a wireless telegraph transmitting apparatus embodying certain circuitual arrangements described in my prior patents and in which, for a given frequency of electrical vibration, a maximum capacity may be employed in the closed oscillating circuit.

Other objects of my invention are to produce a compact and readily adjustable transmitting apparatus which shall consist of the minimum number of parts.

The drawings which accompany and form a part of this specification illustrate several embodiments of my invention.

In the drawings, Figure 1 is an elevation, partly in section, of the preferred form of my invention; Fig. 2 is a plan view thereof; and Fig. 3 is a plan view of a modification.

In the figures, 1 represents the outer wall, and 2 represents the inner wall of a two-walled spark-gap muffler consisting of porcelain or other suitable material and provided with lower ventilating holes, 19, 20, and an upper ventilating flue formed by the hollow bushing 5. The spark electrodes 3, 4 pass through the inner wall 2 and are secured to the outer wall 1, terminating in binding posts 3', 4'. The bushing 5 is secured to the outer wall by the nuts 5', 5", and affords a pivot about which the drum 7 may be rotated. L represents a helix of stout brass or copper wire wound upon said drum and secured at its lower end to the collar 13 which fits over the bushing 5, so that the drum and its helix may be rotated and the latter remain in electrical contact with the bushing 5. To facilitate the rotation of the drum, the base 8 may be provided with casters 6, which rest upon the top of the muffler 1.

11 and 11' are flats trips of brass or copper, secured to the posts 17, 17', respectively,

and carrying at their upper ends clips a, b, which embrace the helix L, so that by the rotation of the latter, the amounts of said helix which are included in the antenna and in the closed oscillating circuit, and therefore the inductance of these elements, may simultaneously be varied. The antenna is connected to the post 17' and the lead to earth is connected to the post 3'; in which the spark electrode 3 terminates.

C, C' represent condensers of any suitable type, such for example, as plate condensers consisting of metallic plates, or else tin-foil mounted on glass plates, immersed in oil or other suitable dielectric. As shown in Fig. 1, two such condensers connected in series may be employed.

In long-distance high-power wireless telegraph systems, there is one most efficient arrangement of the spark gap, the condenser and the helix, and when this arrangement has been found but little adjustment or variation of the apparatus is necessary. Therefore in the apparatus herein described the length of spark-gap, the size of the condensers, and the amount of inductance included in the antenna and oscillating circuit are practically fixed. In order to absorb from the dynamo, or other prime source of energy, the maximum amount of energy, the capacity of the condensers, other things being equal, should be as large as possible for a given frequency, and it is desirable that all the inductance of said oscillating circuit should be concentrated in the helix and not distributed throughout the leads. A certain minimum limit to the amount of inductance in the oscillating circuit is interposed by the necessity for efficient linkage between said circuit and the antenna. The smaller this inductance, the greater may be the capacity of the condenser for a given frequency which frequency cannot fall below a certain limit without reducing the radiating efficiency of the system. Hence all the inductance existing in the leads serves only to reduce the capacity of the condenser which may be employed in the oscillating circuit.

In order to render possible the employment of a condenser of maximum capacity for a given frequency, I make the leads in the oscillating circuit of relatively large wire, or of flat strips, of brass or copper and of the shortest possible length, so that said leads shall have very small and practically negli-

gible inductance as compared with that of the helix. Accordingly, I mount the helix on top of the muffler and connect the lower end 12 of the helix which is connected to the 5 collar 13 to the top of the electrode 3 by a short conductor and connect the electrode 4, through the post 4', and conductor 10 to one terminal of the condenser C which is placed in close proximity to the muffler, while the 10 other terminal of the condenser C is connected to one terminal of condenser C', arranged alongside of C and also in close proximity to the muffler. The circuit is completed by a short connection from C' to 17 and 15 by the conductor 11. It will thus be seen that the compact arrangement of apparatus shown in Fig. 1, as well as the size and shape of the leads employed, produces an oscillating circuit in which practically all the inductance 20 lies in the helix. If three condensers in series are employed, I prefer to connect them in the delta arrangement shown in Fig. 3.

In long distance commercial wireless telegraph transmitting systems, the apparatus 25 is standardized, so that when the apparatus has been once installed very little adjustment is needed. However what adjustment is rendered necessary by varying conditions, as well as the initial adjustment, is afforded 30 by the slight rotation of the drum 7, by which rotation the natural periods of the antenna and closed oscillating circuit may be made equal.

I do not wish to be limited to the exact 35 construction or arrangement of parts shown herein inasmuch as many variations may be made therein without departing from the spirit of my invention.

I claim:

40 1. In a wireless telegraph transmitter, spark electrodes, a double-walled ventilated

muffler inclosing the same, a helix mounted on said muffler and electrical connections from said electrodes to said helix.

2. In a wireless telegraph transmitter 45 spark electrodes, a double-walled ventilated muffler inclosing the same, a rotatable helix mounted on said muffler and electrical connections from said electrodes to said helix.

3. In a wireless telegraph transmitter, 50 spark electrodes, a muffler inclosing the same, a rotatable helix mounted on said muffler, an electrical connection from one of said spark electrodes to one end of said helix, a conducting member adapted to travel along said helix when the latter is rotated, an electrical connection from said member to the other of said spark electrodes and a plate condenser included in said electrical connections.

4. In a wireless telegraph transmitter, 55 spark electrodes, a muffler inclosing the same, a bushing fixed to and extending through the upper wall of said muffler, a drum pivoted to said bushing by a collar making electrical contact therewith, and a helix mounted on 60 said drum and electrically connected with said collar.

5. In a wireless telegraph transmitter, 65 spark electrodes, a double-walled muffler inclosing the same, a bushing fixed to the outer 70 wall and extending through the inner wall of said muffler, a drum pivoted to said bushing by a collar making electrical contact therewith, and a helix mounted on said drum and electrically connected with said collar.

In testimony whereof, I have hereunto subscribed my name this 26th day of Jan., 1906.

LEE DE FOREST.
